FIG. 2

FIG. 1

INVENTOR
W.M. Evensen

John H. Morgan
ATTORNEYS

UNITED STATES PATENT OFFICE.

WILLIAM M. EVENSEN, OF CHICAGO, ILLINOIS, ASSIGNEE TO GOSS PRINTING PRESS COMPANY, OF CHICAGO, ILLINOIS, A CORPORATION OF ILLINOIS.

CAM.

1,302,024.

Specification of Letters Patent. Patented Apr. 29, 1919.

Original application filed November 30, 1915, Serial No. 64,273. Patent No. 1,247,943. Divided and this application filed November 18, 1917. Serial No. 201,725.

To all whom it may concern:

Be it known that I, WILLIAM M. EVENSEN, a citizen of the United States, residing at Chicago, county of Cook, and State of Illinois, have invented certain new and useful Improvements in Cams, of which the following is a specification.

The invention relates to a cam for giving variable throw or travel to the actuated or driven part or mechanism, and to such a cam having means or capabilities for simple, rapid and yet exceedingly nice and exact adjustment of the kind described.

Further objects and advantages of the invention will be set forth in part hereinafter and in part will be obvious herefrom, or may be learned by practice with the invention; the same being realized through the instrumentalities and combinations pointed out in the appended claims.

The invention consists in the novel parts arrangements, constructions, combinations and improvements herein shown and described.

The accompanying drawings herein referred to and constituting a part hereof, illustrate one embodiment of the invention, and together with the description serve to explain the principles thereof.

Of the drawings:—

Figure 1 is a face view or front elevation of the cam and shows a coöperating lever arm, and

Fig. 2 is an edge view or side elevation looking at Fig. 1 from the right.

This application is a division of my Patent No. 1,247,943, filed November 30, 1915. In that patent the cam is shown and described applied to and constituting a part of the inking mechanism of a printing press, and from said patent certain objects and advantages of the invention may be ascertained in connection with the description of the therein exemplified embodiment or adaptation of the present invention.

In the embodiment illustrated by way of example in the accompanying drawings, the cam is shown mounted upon a shaft 1 (corresponding to the shaft 26 in the parent application), the cam having a hub 2 encircling the shaft, the cam being longitudinally and angularly positioned and held upon the shaft in any suitable or approved manner. The body of the cam as embodied comprises a

disk 3, preferably integral with the hub 2. 55 In such exemplified form the coöperating lever arm 4 and roller 5, (corresponding to arm 23 and roller 24 in the parent application) operate on the face of the cam disk 3.

As embodied, a portion of the face of the 60 cam 3 consists of a segmental spring plate 6, attached to the surface of the cam 3 in a suitable manner, as by screws 7 and 8, said plate being mounted preferably to form a continuous cam surface with the solid or 65 non-resilient face of the disk 3.

The spring plate 6 is rendered adjustable as embodied, by an adjusting screw 9 threaded through an aperture in the cam disk 3, and with its point bearing on the under or 70 inner side of the spring or resilient plate 6. The screw 9 may be turned by means of its head 10 and furnishes an exceedingly nice and exact adjustment for the throw or travel of the lever 4 and the parts or mechanism operated thereby. The cam may also be positioned longitudinally of the shaft as may be found desirable or necessary.

It will be understood that changes may be made from the detailed construction as 80 shown and described, within the scope of the appended claims, without departing from the principles of the invention or sacrificing its chief advantages.

What I claim as my invention is:—

1. A cam mechanism including in combination a cam lever, a shaft, a substantially circular cam disk mounted on the shaft and having its side face coöperating with the cam lever, a resilient arcuate strip constituting a part of the operative surface of the cam, said strip being fastened to the cam disk, and a screw threaded through the cam disk and engaging the inner side of said resilient strip. 95

2. A cam mechanism including in combination a cam having a solid body portion and a resilient member constituting a portion of the operative face of the cam, a screw engaging said resilient member to vary its 100 position and a cam lever device engaging both with the solid and resilient portions of said cam.

3. A face cam having a resilient member constituting a part of its face and of the cam 105 track and means for raising and lowering said member to vary and regulate the throw of the cam.

4. A cam having a body and a resilient member continuous therewith, the cam track passing over the cam body and over the resilient member, and means for raising and 5 lowering the resilient member to vary and regulate the throw of the cam.

In testimony whereof, I have signed my

name to this specification, in the presence of two subscribing witnesses.

WILLIAM M. EVENSEN.
